UNITED STATES PATENT OFFICE.

EDGAR N. DOLLIN, OF SYRACUSE, NEW YORK.

FLUID-PRESSURE CONTROLLER.

Application filed July 23, 1919. Serial No. 312,848.

To all whom it may concern:

Be it known that I, EDGAR N. DOLLIN, of Syracuse, in the county of Onondaga, in the State of New York, have invented new and 5 useful Improvements in Fluid-Pressure Controllers, of which the following, taken in connection with the accompanying drawings, is a full, clear, and exact description.

This invention relates to certain improvements in fluid pressure controllers for piston motors and other uses in which it is desired to apply a relatively higher power or force at certain intervals than at other intervals in the performance of specific work 10 such for example, as the operation of a mold holder or die-carriage of die-casting machines in which a greater power or force is required to hold the mold in operative position to receive the molten metal, as the latter is forced thereinto under relatively 15 higher pressure than that required to move the mold to and from its receiving position.

In devices of this character, it is customary to exhaust the entire pressure fluid 20 to the atmosphere during such operation which requires the restoration of the full power before such operation can be repeated, and results, not only in an unnecessary use and considerable loss of power, but also 25 renders the operation of the movable element of the motor, such as a piston, more or less impulsive and unstable so that when used in die-casting machines it is liable to produce certain imperfections or breakages 30 in the castings.

On the other hand, it is well known that the action of the movable element of a fluid pressure operated motor is greatly steadied 35 by the application of some pressure, even though unequal, to opposite sides or ends thereof; and the main object of my present invention is to not only produce a great saving of power and time in the performance 40 of work adapted to be done by fluid pressure, but also to obtain a steadier action of the fluid operated element of the motor, and at the same time to permit the application 45 of greater power at certain intervals than at other intervals in the performance of the work, and particularly at the conclusion of 50 the stroke of the piston in die-casting.

Other objects and uses relating to specific parts of the controller will be brought out in the following description.

In the drawings,—

Figure 1 is a longitudinal sectional view 55 of a piston motor and my improved controller mounted thereon adjusted to shift the piston from right to left.

Figure 2 is a sectional view of the controller taken in the plane of line 2—2 Figure 1.

Figure 3 is a sectional view of the same controller and adjacent portion of the motor except that the piston has been shifted to 65 the left hand end of the cylinder and that the valve is adjusted to apply the maximum power to the piston as it approaches or reaches the limit of its forward stroke.

Figure 4 is a sectional view of the controller taken in the plane of line 4—4 Figure 3.

Figure 5 is a sectional view similar to Figure 4 except that the valve is adjusted to cause the return of the motor piston.

Figure 6 is a longitudinal sectional view 75 of the controller taken in the plane of line 6—6 Figure 2.

Figure 7 is a diagrammatic view of the motor and its controller together with means 80 for supplying the fluid under pressure to the controller and motor.

In order that my invention may be clearly understood, I have shown my improved controller in connection with a piston motor 85 which may be used to perform various kinds of work, as for example, the operation of a mold holder of a die-casting machine, (not shown) but it is evident that the same controller may be used for many 90 purposes other than the operation of machinery, as for example, in producing variable fluid pressures in sequence.

To this end, the controller comprises a valve case —1— containing, in this instance, a rotary valve —2— and having its base secured to one side of a motor cylinder —A— and provided with a pair of diametrically opposite service ports —3— and —3'— communicating with similar ports 100 —a— and —a'— in the adjacent wall of the cylinder —A—, said ports being, in this instance, spaced apart a distance corresponding approximately to the stroke of the motor piston as —A'— which is movable in 105 the cylinder —A—, and is provided with a piston rod —b— extending outwardly through a gland —b'— in one end of said

cylinder for connection with the mold holder for a die-casting machine or for performing any other work to which it may be adapted.

5 The case —1— is also provided with a pair of diametrically opposite relatively high pressure and low pressure ports —4— and —4'— disposed in a plane at right angles to that of the ports —3— and —3'—, both 10 of which are in constant communication with a valve chamber —2'— in which the valve —2— is movable.

The valve chamber —2'— is preferably circular or cylindrical while its inner end 15 wall is substantially flat to form an abutment against which the inner end of the valve —2— is seated, said valve being also circular or cylindrical and rotatable in the chamber, its inner end being substantially 20 flat and seated against the inner end wall of the chamber —2'—, and is provided with an annular flange —5— of substantially the same diameter as that of the chamber so as to fit snugly therein, the remaining portions 25 of the valve being reduced in diameter and extended outwardly through the open end of the chamber —2'—.

A cap ring —6— is secured by bolts —7— to the outer end face of the main body of 30 the valve case —1— and is provided with an annular shoulder —8— extending slightly beyond the adjacent peripheral walls of the chamber —2'— and fitting snugly upon the periphery of the adjacent portions of the 35 valve —2—, the outer face of said flange being V-shaped to form a seat for a packing ring —9— which is held in place by a gland —10— also surrounding and engaging the periphery of the valve, said gland being ad- 40 justably secured to the cap ring —6— by bolts —11—.

The flanges —5— and —8— are spaced some distance apart to form an intervening annular chamber —12— which is a part of 45 the valve chamber —2'— and constitutes what may be termed a "distributing chamber" extending entirely around the valve.

The port —4— extends radially directly into the distributing chamber —12— and is 50 connected by a pipe —13— to a high pressure source of fluid supply, such as a tank —14— or high pressure pump —15—, although, in the diagrammatic view shown in Figure 7, both the tank and the pump 55 are shown as connected to each other by a pipe —13'—.

The diametrically opposite port —4'— ex- 60 tends radially to the center of the case where it communicates with an axially ex- 65 tending passage —16— which is in constant communication with a central passage —17— in the base of the valve —2—, the outer end of said port —4'— being connected by a pipe —18— to a relatively low pressure source of fluid supply consisting

of a tank —19— or a low pressure pump —20—, although, the latter is shown in the diagrammatic view in Figure 7 as connected to the pressure tank —19— by means of a pipe —18'—.

If air is used for the pressure fluid, it is taken into the pump —20— at atmospheric pressure and compressed to a higher degree of say one hundred pounds per square inch which is maintained in the tank —19— and 75 its pipe line leading to the port —4'—.

The pump —15—, however, is adapted to receive the pressure fluid under an increased pressure considerably above that of the atmosphere, and as illustrated in the diagrammatic view, Figure 7, its intake is connected by a pipe —21— to the tank —19—, and therefore the pump —15— receives the air under pressure of approximately one hundred pounds per square inch, and is operated to boost that pressure to say an additional one hundred pounds per square inch or to approximately two hundred pounds per square inch in the tank —14— and its pipe line leading to the port —4—.

It is now evident that two distinctly unequal pressures above atmospheric pressure are maintained in the ports —4— and —4'—, as for example, two hundred pounds pressure in the port —4— and one hundred 95 pounds pressure in the port —4'—, both pressures being employed to perform certain work, such as the operation of the piston —A'— as controlled by the valve —2— hereinafter more fully described.

The inner end wall of the valve chamber —2'— is provided with a pair of diametrically opposite axial ports —22— and —22'— at equal distances from the axis of said valve chamber and at opposite sides of 105 the central port —16—, and serve to connect the valve chamber with the inner ends of radial passages —23— and —23'— which are formed in the valve case —1— and have their outer ends communicating with the 110 ports —3— and —3'—, respectively, as shown more clearly in Figures 1 and 3, said valve case being also provided with an axially extending passage —24— between the central port —16— and the port —22'— for connecting the valve chamber with an atmospheric chamber —25—, Figures 1, 3 and 6, which in turn communicates with the atmosphere through a radial passage —26— from one side of the chamber —25—.

The valve —2— is provided with a series of (in this instance, six) ports —27—, —28—, —29—, —30—, —31— and —32— arranged sequentially in substantially equal spaced relation about the axis of the valve, 125 the port —28— forming a circumferentially extending continuation of the port —27— which together with the port —29— open through the periphery of the valve.

The ports —30— and —32— are connected 130

to each other and to the central port —17— by a common chamber —33— and are, therefore, in constant communication with the lower pressure port —4'— through the central passage —16— in the valve case —1— while the intermediate port —31— is connected by a radial passage —34— to an atmosphere port —35— which is movable into and out of registration with the atmosphere port —24— in the valve case —1— Figure 3 as the valve is moved to different positions presently described. The ports —27—, —28—, —29—, —30—, —31—, and —32— all open through the inner end face of the valve, but there is no direct communication between the ports —30—, —31—, and —32— and the circumferential chamber —12— and in view of the fact that the first named ports are arranged circumferentially in sequence 20 at an angle of substantially 60° to each other, the valve may be operated through the medium of a suitable handle —36— to control the pressure fluid as follows:

Assuming, for example, that the piston 25 —A'— is to be operated by fluid pressure as air to perform some useful work and that it has just reached the limit of its stroke toward the right hand port —a—, Fig. 1, ready to begin its forward or working 30 stroke, then the valve —2— will be adjusted rotarily from a certain position which, for convenience of description, will be termed the starting position shown in Fig. 5, through an arc of 60° or to the position 35 shown in Fig. 2 in which the diametrically opposite ports —27— and —30— will be registered respectively with the ports —22— and —22'— leading to the cylinder ports —a— and —a'— through the passages —23— 40 and —23'— at which time the ports —29—, —31—, and —32— will be cut off from communication with the ports —22— and —22'—. When the valve is in this position, the high pressure fluid, I will say two hundred 45 pounds to the square inch, entering the inlet port —4— and circumferential chamber —12— communicating therewith, passes through ports —27—, —22—, and —a— into the right hand end of the cylinder —A— 50 to exert a corresponding pressure upon the piston —A'— to move it toward the port —a— while the low fluid pressure, of say one hundred pounds, per square inch, entering the port —4'—, passes through the central ports —16— and —17— into the chamber —33— and thence to the registering ports —30— and —22'— and port —a'— into the left hand end of the cylinder, thus 55 producing a corresponding pressure in opposition to that at the opposite end of the piston, that is while the pressures at opposite ends of the piston are considerably above atmospheric pressure, that at the right hand end is considerably greater than that at the 60 left hand end and causes the piston to move 65

through its working stroke or to the position shown in Fig. 3.

When the piston is used for the operation of a die casting mold to and from the outlet of the melting chamber to receive the 70 molten metal which is usually discharged under high pressure, it is necessary to hold the piston actuated mold support against such pressure with a force considerably greater than that required to move the mold 75 support to and from the work.

Under these conditions the valve is again adjusted by hand another 60° turn in the same direction or from the position shown in Fig. 2 to that shown in Fig. 4, in which 80 later position the port —27— will still maintain communication with the ports —22— and —a— through the circumferentially elongated port —28— while the ports —31— and —35— will be registered respectively 85 with the port —22'— and atmosphere port —24— thus permitting the escape of lower pressure air from the left hand end of the cylinder to the atmosphere while still maintaining the high pressure in the right hand 90 end of the cylinder without any appreciable counter pressure upon the piston.

That is, when the valve is adjusted to the position shown in Fig. 4, the air under the relatively low pressure, in this instance, one 95 hundred pounds, per square inch, at the left hand of the piston, Fig. 3, is free to escape through the passages —a'—, —3'— and —23'— in the cylinder and valve case —1— and thence through the port —31— and 100 passage —34—, and atmosphere port —35— to the atmosphere chamber —25— whence it escapes to the atmosphere at 26, figure 6 and thereby using the full air pressure. in this instance two hundred pounds per 105 square inch, to be exerted upon the right hand end of the piston as distinguished from the previous net pressure of one hundred pounds, the difference between the two opposing pressures, it being understood that 110 when the valve port —31— is registered with the port —22'—, the port —27— is receiving the higher pressure from the chamber —12— through the ports —27— and —28—, which later is then in communication with the port —22— and through the passage —23— with the cylinder port —a—, and that the ports —29—, —30—, and —32— are cut off from communication 115 with the cylinder ports.

Now, in order to restore the piston and the parts operated thereby to their normal positions, the valve is returned to its starting position shown in Fig. 5 so that the ports —32— and —29— will register respectively with the ports —22— and —22'— and the same time cut off communication with the port —35— and the atmosphere and also between the ports —27—, —28—, —30—, and —31— and the cylinder ports. 130

In this position of the valve the high pressure air is free to flow from the chamber —12— through the registering ports —29— and —22'— and thence through the 5 passages —23'— and —a'— to the left hand end of the cylinder while the lower pressure air is free to flow from the port —4'— through the central passages —16— and —17— into the chamber —33— and thence 10 through the registering ports —32— and —22— and passages —23—, —3—, and —a— into the right hand end of the cylinder, the higher pressure at the left hand end of the cylinder serving to return the piston 15 to its starting position shown in Fig. 1.

Although I have shown and described a specific form of rotary valve and valve case for controlling the passage of air through the delivery ports as —a— and —a'— under different pressures both greater than atmospheric pressure for effecting the operation of a piston, it is to be understood that I do not limit myself to that particular type of valve and valve case nor to the 25 particular work performed by the different air pressures but rather contemplate the use of any suitable mechanism by which a fluid under pressure may be delivered through separate ports under different pressures 30 above atmospheric pressure in such manner that the lower pressure fluid may be returned to the intake of the higher pressure, producing device without material reduction of such lower pressure so that the work 35 of the higher pressure producing device in boosting the lower pressure is reduced to an amount corresponding to such lower pressure except for the negligible losses by leakage and temperature changes.

40 The operation briefly described is as follows. The atmospheric air is drawn through the intake of the low pressure pump —20— and delivered at a higher pressure to the tank —19— and thence through the pipe —18— and ports —4'—, —16— and —17— to the chamber —33— said low pressure air being also delivered from the tank —19— through the pipe —21— to the intake of the high pressure pump —15— where it is 45 boosted to a still higher pressure and delivered to the tank —14— through the pipe —13'— and thence through the pipe —13— and port —4— to the chamber —12—. Now, assuming that the valve is adjusted to 50 the position shown in Fig. 5 then the high pressure port —4— will be in communication with the left hand port —a'— Figs. 1 and 3 while the low pressure port —4'— will be in communication with the right hand port —a—.

55 By shifting the valve to the position shown in Fig. 2 the pressures at the ports —a— and —a'— will be reversed and then by again shifting the valve to the position 60 shown in Fig. 4, the low pressure port will

be brought into communication with the atmosphere port —35— to enable the high pressure to exert itself full force in the performance of this work after which the valve 70 may be returned to its starting position shown in Fig. 5 to again reverse the pressures at the ports —a— and —a'— and simultaneously cut off communication of both ports with the atmosphere, it being evident that the variable pressures at the ports 75 —a— and —a'— may be utilized for operating the same member in reverse directions or for performing work upon different devices and, therefore, I do not limit myself to the use to which these differential pressures 80 may be applied. The ports —4— and —4'— through which the power fluid is adapted to circulate may be termed the power or pressure ports while the ports —3— and —3'— through which the fluid 85 passes to perform the work or service may be termed the working or service ports.

What I claim is:—

1. A fluid pressure controlling mechanism having pressure ports and separate service 90 ports, means for maintaining unequal pressures above atmospheric pressure at both of the pressure ports, respectively and means for simultaneously connecting either of the pressure ports with one of the service ports 95 and the other pressure port with the other service port.

2. A fluid pressure controlling mechanism having pressure ports and separate service 100 ports, means for producing unequal pressures above atmospheric pressure at both of the pressure ports, respectively and means for connecting one of the pressure ports with one of the service ports and the other pressure port with the other service port, and 105 means for venting one of the service ports to the atmosphere without varying the pressure at the other service port.

3. A fluid pressure controlling mechanism having pressure ports and separate service 110 ports, means for maintaining different pressures greater than atmospheric pressure at both of the pressure ports, and means for simultaneously connecting the higher pressure port with either of the service ports and 115 the lower pressure port with the other service port.

4. A fluid pressure controlling mechanism having a high-pressure port and a low-pressure port and separate service ports, means 120 for maintaining a fluid pressure at the low pressure port greater than atmospheric pressure, means for maintaining a fluid pressure at the high pressure port greater than that at the low pressure port, 125 means for connecting the high pressure port with one of the service ports, additional means for connecting the low pressure port with another service port, and means for venting the last named service 130

port to the atmosphere and simultaneously cutting off its communication with the low pressure port.

5. A fluid pressure controlling mechanism having a high-pressure port and a low-pressure port and separate service ports, said mechanism including a valve having means when adjusted to one position for connecting the high pressure port with one of the 10 service ports and additional means for connecting the low pressure port with the other service port and also provided with means when adjusted to a different position for venting the last named service port to the 15 atmosphere, and additional means when in the last named position for cutting off communication between the second named means and the low pressure port while the first named means maintains communication between 20 the first named service port and the high pressure port.

6. A fluid pressure controlling mechanism comprising a valve case having a valve chamber, a high-pressure port, a low pressure port and service ports, means for carrying pressure greater than atmospheric pressure at the low pressure port, means for carrying pressure greater than the last named pressure at the high pressure port, a valve for alternately connecting the service ports with the pressure ports, said valve having means for closing the low pressure port and additional means for simultaneously venting one of the service ports to the atmosphere while communication is maintained between the high pressure port and the other service port.

7. A fluid pressure controlling mechanism comprising a valve case having a high-pressure port, a low-pressure port and service ports, means for maintaining fluid pressure at the low pressure port greater than atmospheric pressure, means for maintaining fluid pressure at the high pressure port greater than that at the low pressure port and a valve adjustable to one position for connecting the high pressure port with one of the service ports and the low pressure port with the other service port and to another position for cutting off communication between the low pressure port and the last named service port and for venting said last named service port to the atmosphere.

8. A fluid pressure controlling mechanism comprising a valve case having pressure ports and service ports, means for maintaining fluid pressure at one of the pressure ports greater than atmospheric pressure, means for maintaining fluid pressure at the other pressure port greater than that at the first-named pressure port, and a valve adjustable to one position for connecting the higher pressure port with one of the service ports and the lower pressure port with the other service port and to another position

for cutting off communication between the lower pressure port and the last named service port and for venting said last named service port to the atmosphere, said valve being adjustable to another position for connecting the higher pressure port with the last named service port and the lower pressure port with the first named service port.

9. A fluid pressure controlling mechanism comprising a valve chamber having pressure supply ports and service ports, means for maintaining unequal pressures at the supply ports respectively, a valve adjustable to one position for connecting the higher pressure port to one of the service ports and the lower pressure port to the other service port and to another position for connecting the higher pressure port to the last named service port and the lower pressure port to the first named service port.

10. A fluid pressure controlling mechanism comprising a valve chamber having pressure supply ports and service ports, means for maintaining unequal pressures at the supply ports respectively, a valve adjustable to one position for connecting the higher pressure port to one of the service ports and the lower pressure port to the other service port and to another position for connecting the higher pressure port to the last named service port and the lower pressure port to the first named service port and to a third position for cutting off communication between the lower pressure port and both of the service ports and for venting one of the service ports to the atmosphere.

11. A fluid pressure controller having service ports and pressure ports, in combination with a controlling member movable at will to different positions, and means actuated by said member when moved to one position for simultaneously connecting one of the pressure ports with one of the service ports and the other pressure port with the other service port.

12. A compressed air circulating system having service ports, pressure ports, and a source of supply for compressed air having an intake connected to one of the pressure ports and an outlet connected to the other pressure port, the connection between the intake and its pressure port containing air under pressure greater than atmospheric pressure, and means for connecting either pressure port with either service port and the other pressure port with the other service port.

13. A fluid pressure controller having service ports and pressure ports, in combination with a controlling member movable at will to different positions, and means actuated by said member when moved to one position for connecting one of the pressure ports with one of the service ports and simultaneously cutting off communication be-

tween the other pressure port and its service port and venting the last named service port to the atmosphere.

14. A fluid pressure controller having 5 service ports and pressure ports, in combination with means for maintaining unequal pressures above atmospheric pressure at the pressure ports, a controlling member movable at will to different positions, and means 10 actuated by said member when moved to one position for connecting the higher-pressure port to one of the service ports and the lower-pressure port to the other service port.
15. A fluid pressure controller having 15 service ports and pressure ports, in combination with means for maintaining unequal

pressures above atmospheric pressure at the pressure ports, a controlling member movable at will to different positions, and means actuated by said member when moved to 20 one position for connecting the higher-pressure port with one of the service ports and for simultaneously cutting off communication between the lower-pressure port and the other service port and venting the last 25 named service port to the atmosphere.

In witness whereof I have hereunto set my hand this 10th day of July, 1919.

EDGAR N. DOLLIN.
